(57) **CLAIM**

The ornamental design for scoop, as shown and described.

DESCRIPTION

FIG. 1 is a perspective view of the scoop embodying the new design;

FIG. 2 is a top view thereof;

FIG. 3 is a bottom view thereof;

FIG. 4 is a right side elevational view thereof, the left side elevational view being a mirror image;

FIG. 5 is a front view thereof; and,

FIG. 6 is a rear view thereof.

The broken lines in FIGS. 1-4 represent environmental structure and form no part of the claimed design.
